UNITED STATES PATENT OFFICE.

ALBERT B. RYPINSKI, OF BROOKLYN, NEW YORK, ASSIGNOR TO THOMAS E. MURRAY,
OF BROOKLYN, NEW YORK.

SERVICE SWITCH.

Application filed April 2, 1921. Serial No. 457,870.

To all whom it may concern:

Be it known that I, ALBERT B. RYPINSKI, a citizen of the United States, residing in Brooklyn, county of Kings, State of New York, have invented certain new and useful Improvements in Service Switches, of which the following is a specification.

My invention provides certain improvements applicable to the service switches leading from the service lines of electric companies to the houses, factories, etc. of customers. The invention is particularly useful in connection with the occasional testing of the customer's meter by the electric company, and provides means whereby such testing can be most easily done and with the least interference with the conditions.

The accompanying drawings illustrate embodiments of the invention.

Fig. 1 is a plan of the connections, switch blades and fuses in the switch box leading into the meter and from the house, for a three-wire system;

Fig. 2 is a perspective view thereof with the house switch open;

Fig. 3 is a similar view with all connections to the meter open so that the meter may be tested;

Fig. 4 is a horizontal section of a detail;

Fig. 5 is an elevation of one of the devices for connecting a house switch with a service switch;

Fig. 6 is a horizontal section of the same on the line 6—6 of Fig. 5;

Fig. 7 is a diagram showing the application of the invention to a two-wire system.

Referring to the embodiment of the invention illustrated, the service wires 1, 2 and 3 lead into the switch box and the house wires, 4, 5 and 6 lead therefrom to the house. 7 and 8 are coils in the meter. The wires 1 and 4 lead into and out of the first coil and the wires 3 and 6 into and out of the second coil. The wires 2 and 5 constitute a neutral line which does not pass through the meter.

The wire 1 leads first to a fuse terminal 9 thence through a fuse 10 to the opposite terminal 11 and thence through a blade or switch 12, pivoted on the terminal block 11, to a terminal block 13 with the usual spring blades 14 for engagement with the end of the switch blade, the terminal block

13 being connected to the coil 7. From the coil 7 the outgoing wire is connected to a switch terminal block 15 with switch blocks 16 adapted to engage the free end of a blade switch 17 which is pivoted on a block 18 to which the house wire 4 is directly connected. Similarly the other active service wire 3 is connected through fuse terminal 19, fuse 20 and terminal block 21 carrying pivoted blade switch 22 to the spring blade 23 of a terminal block 24 which is connected to the meter coil 8. And the outgoing wire from this coil leads through the terminal block 25 and spring blades 26 to the free end of the blade 27 which is pivoted on the terminal block 28 which is connected directly to the house wire 6.

The neutral service wire 2 leads to a terminal block 29 carrying a pivoted blade switch 30 engaged by a spring blade 31 on a block 32 which is connected directly to the neutral house wire 5.

The three switches 17, 30 and 27 constitute a triple pole house switch and are generally connected together as for example by means of a cross-bar 33, Fig. 2, with an operating handle 34. When the user wishes to discontinue the supply he opens this triple pole switch as indicated, which disconnects the several house wires, but leaves the wires unbroken leading from the service lines into the meter and with the fuses 10 and 20 in the lines.

When the meter is to be tested it is desirable to be able to continue the supply from the service lines to the house, shunting out the meter and leaving its terminals free for connection to the testing equipment. For this purpose I provide means for establishing proper electric connections between the service switches and the house switches so that although the switches are open to break the connections to the meter, yet the supply to the house remains unbroken, and the fuses remain in the operating circuit. This position is shown in Fig. 3 and a convenient device is shown in Figs. 5 and 6 for establishing the necessary electric connections and also for locking the necessary switches together mechanically so that they can be opened by a single operation. These connecting devices are indicated as a whole by the numeral 35. Figs. 1 (where their position is indicated 110

in dotted lines) and 3 show that they are meant to connect the switches 12 and 17 and the switches 27 and 22. This device comprises arms electrically connected together 5 and adapted to engage the two blades which are to be connected. The connecting member is made of a pair of plates 36 and 37 having arms 38 and 39 respectively spaced apart so as to frictionally embrace the 10 switch blades. These two plates are welded or otherwise fastened together. A spindle 40 passes loosely through them and carries fixed on its lower end a cross-piece 41 whose length is sufficient to span the under edges of the two 15 blades 12 and 17 when it is turned in the position of Fig. 5, and which can also be turned to the position of Fig. 6, which shows that its width is sufficient to permit 20 it to be passed down between the blades. With the cross-piece 41 in the position of Fig. 6 the connecting member is pressed down so as to embrace the two switch blades. The spindle is then pushed down 25 by the handle 42 until the cross-piece 41 lies below the level of the under edges of the switch blades, after which the handle and the spindle 40 are turned to bring the ends of the cross piece under the blades. 30 The connecting device carries also means for pressing the cross-piece up against the blades so as to make good electrical contact and to lock the parts together mechanically. For this purpose there is mounted on the 35 connecting member a cam 43, through which the spindle passes freely, and there is fixed on the spindle a co-operating cam 44. These cams are so located as to permit the spindle to assume its lowest position with the cross- 40 piece arranged longitudinally between switch blades. Then as the handle and spindle are turned the cam 44 rides up on the cam 43 until the cross-piece has been turned to a transverse position, the parts 45 being so proportioned that at the same time the cross-piece will bear hard up against the under edges of the switch blades. With the straight blade type of switches shown the connecting devices may be applied at any 50 point in the length of the switches and against the lower edges of the blades. But the switches, of course, may be of other designs and provided with other edges for engagement by the clamping cross-piece. 55 The two connecting and clamping devices being fastened in place, a lifting of the regular switch handle 34 will open the two switches 12 and 17 and also the switches 27 and 22, but will leave the house wires connected to the appropriate service wires through the shunting devices 35 instead of through the meter coils. The fuses 10 and 20 will remain in their appropriate positions in the line. The terminal blocks 13, 60 15, 24 and 25 will then constitute free termi-

nals of the meter coils, for attachment of the testing equipment. It will be observed that the connecting device 35 is independent of the permanent equipment within the switch box. Also it does not require any 70 modification of the usual simple forms of switch and switch and fuse terminals. The fuses may be inserted at any usual or suitable points between the service lines and the corresponding meter terminals. When inserted at the points illustrated they will be left in the house line during a testing operation. The invention is applicable also to various switching arrangements other than that shown and to equipments in which 80 there is no fuse directly included. It is applicable also to installations having terminals which lead to some other apparatus than a meter, which apparatus is to have its terminals isolated for connection to a testing 85 or other instrument.

In order to maintain the house supply, the switch 30 which is normally connected mechanically to the house switches 22 and 27 so as to open with them, must remain 90 closed. Therefore, this switch 30 is provided with a detachable connection to the switch operating handle 34 or cross-bar 33. The switch blade has a transverse flange 45 which enters freely a groove 46 extending 95 transversely across the face of the bar 33. A pin 47 extends through the handle 34, with a button 48 on its outer end by which it may be manipulated and with a collar or shoulder 49 near its inner end against which 100 bears a spring 50 tending to force the end of the pin into a hole in the flange of the switch blade and to lock the two together as shown. The end of the pin 47 may be beveled on its underside so that, assuming the 105 switch 30 closed, the lowering of the handle will cause the pin to snap into engagement with the flange of the switch blade. Or, if the pin is not beveled, the operator can hold it out by means of the button 48 until the 110 parts are in register and then release it. In the ordinary operation of the switch by the customer the central blade 30 will be always held in engagement with the switch operating handle. 115

When the meter is to be tested, however, the operator will hold the button 48 out while lifting the switch handle to the position of Fig. 3, and thus will leave the switch 30 in closed position to maintain the house 120 connection.

In the diagram, Fig. 7, illustrating a two-wire system, the service wire 51 is connected to a fuse 52 and thence to a single blade service switch 53 leading to the meter coil 125 54; the outgoing end of which connects through a single blade house switch 55 with the ingoing house wire 56. With this arrangement, when it is desired to test the meter, its terminals may be isolated by first 130

establishing an electric connection between the house and service switches 55 and 53 and then opening the two together, leaving the house with its regular supply of current 5 through the fuse 52.

Though I have described with great particularity of detail certain embodiments of my invention, yet it is not to be understood therefrom that the invention is restricted to 10 the specific embodiments described. Various modifications thereof in detail and in the arrangement of the parts may be made by those skilled in the art without departing from the invention as defined in the following claims.

What I claim is—

1. The combination with terminals for an electric meter or other apparatus, of a house switch and a service switch, one on a leading in wire and the other on a leading out wire, said switches being separately operable, and means for establishing an electric and a mechanical connection between them by which they may both be disconnected 25 from the said terminals without cutting off the service to the house.

2. The combination with terminals for an electric meter or other apparatus on a three-wire system having two active service wires, 30 of a house switch for each of the three house wires and a service switch for each of the two active service wires, said house switches being operable separately from said service switches, and means for establishing an electric 35 connection between each service switch and the corresponding house switch, and a mechanical connection between said switches so that all wires may be disconnected from said terminals without cutting off the house 40 service.

3. A device for connecting a pair of switch blades comprising electrically connected arms adapted to engage the blades and means for clamping the blades to the corresponding arms.

4. A device for connecting a pair of switch blades comprising electrically connected arms adapted to engage the blades and carried by a handle, and means operated by said 50 handle for clamping the blades to the corresponding arms.

5. A device for connecting a pair of switch blades comprising electrically connected arms adapted to engage the blades, a spindle 55 carrying said arms and carrying a cross-

piece at its lower end adapted to be inserted between said blades and turned to engage under edges thereof, and means for pressing said cross-piece upward against the under edges of the blades to clamp them against 60 the corresponding arms.

6. The combination with terminals for an electric meter or other apparatus on a three-wire system having two active service wires, 65 of a house switch for each of the three house wires and a service switch for each of the two active service wires, said house switches being operable separately from said service switches, a fuse for each service wire and means for establishing an electric connection 70 between each service switch and the corresponding house switch, and a mechanical connection between said switches so that all wires may be disconnected from said terminals without cutting off the house service. 75

7. The combination with terminals for an electric meter or other apparatus on a three-wire system having two active service wires and two active house wires, of a house switch for each of the two active house wires and a 80 service switch for each of the two active service wires, said house switches being operable separately from said service switches and means for establishing an electric connection between each service switch and the 85 corresponding house switch and a mechanical connection between said switches so that all active wires may be disconnected from the corresponding terminals without cutting off the house service. 90

8. The combination with terminals for an electric meter or other apparatus on a three-wire system having two active service wires and two active house wires, of a house switch for each of the two active house wires and 95 a service switch for each of the two active service wires, said house switches being operable separately from said service switches, a fuse for each active service wire, and means for establishing an electric connection between each service switch and the corresponding house switch and a mechanical connection between said switches so that all active wires may be disconnected from the corresponding terminals without cutting off 100 the house service. 105

In witness whereof, I have hereunto signed my name.

ALBERT B. RYPINSKI.
